(57) **CLAIM**

The ornamental design for a display screen with user interface, as shown and described.

DESCRIPTION

FIG. 1 is a front view of a display screen with user interface showing our new design;

FIG. 2 is a front view of the display screen of FIG. 1 shown on a device;

FIG. 3 is a front view of an alternative embodiment of a display screen with user interface showing our new design; and,

FIG. 4 is a front view of the display screen of FIG. 3 shown on a device.

The broken line showing of the four circles and the remainder of the display screen in FIGS. 1-4, and the device in FIGS. 2 and 4 illustrates unclaimed environment and forms no part of the claimed design.

1 Claim, 4 Drawing Sheets

FIG. 1

FIG. 2

FIG. 3

FIG. 4
